UNITED STATES PATENT OFFICE

HERMANN CHRISTIAN FISCHER, OF VIENNA, AUSTRIA, ASSIGNOR TO THE FIRM:
UNION-SPECIAL-MASCHINENFABRIK GESELLSCHAFT MIT BESCHRANKTER HAF-
TUNG, OF STUTTGART, GERMANY

CUTTING MECHANISM FOR SEWING MACHINES

Application filed April 20, 1923, Serial No. 633,539, and in Germany January 23, 1922.

My invention relates to a cutting mechanism for use in connection with sewing machines and intended to cut incisions into leather or the like, the object of these incisions 5 being to receive the sewing thread which is countersunk thereinto in order to be protected against wear.

In the devices of this kind hitherto in use, the cutter is stationary and performs the cutting while the leather is fed forward, whereby the feeding of the leather is rendered difficult, and even made impossible if particularly hard leather is being treated.

This drawback is obviated, in accordance 15 with my invention, by causing the incisions to be made while the leather is at rest, that is to say, in the intervals between the feeding movements.

My invention further relates to the means 20 for raising and depressing the upper layer of the leather severed by the incision. Heretofore the cutting and raising has been effected by means of a cutter in which the horizontal part of the blade and the vertical edge for 25 raising the upper layer were located in the same vertical plane which rendered the raising of the leather difficult, the width of this layer being further reduced by compression, so that after depression the upper layer 30 would not fully cover the bottom layer. In the cutting mechanism according to the present invention, the raising edge of the cutter is disposed considerably to the rear of the cutting edge, whereby a reduction in width of 35 the raised layer is prevented.

On the other hand, the depressing of the upper layer was hitherto effected by means 40 of a folding ledge which was fixed in relation to the needle and not exchangeable, involving the drawback that the flap on being folded down was liable to buckle if the cutting width of the blade was altered. In the new cutting mechanism according to the present invention, the folding ledge is exchangeable, and a 45 ledge of suitable width may be inserted for every cutting width and this ledge can further be adjusted into the suitable distance with respect to the needle.

In order to be able to get over projecting 50 parts of the leather, the cutting mechanism

is detachably connected with the sole of the presser foot so that it can be lifted temporarily from the working position and does no more engage the leather, whereas the machine continues sewing until the cutting mechanism is lowered again into its former position.

In the drawings affixed to this specification and forming part thereof, two modifications of a device embodying my invention are illustrated diagrammatically by way of example. In the drawings

Figure 1 is a plan of the cutting mechanism in combination with the presser foot and attached to the machine table,

Figure 2 is a plan, partly in horizontal section and drawn to a larger scale.

Figure 3 is a vertical section on the line *b*—*b* in Figure 1.

Figure 4 shows the cutter in five different 70 positions (*a b c d e*).

Figure 5 is a front view.

Figure 6 is a vertical section on the line *c*—*c* in Figure 7.

Figure 7 is a side view corresponding to 75 Figure 5.

Figure 8 is a vertical section of the parts shown in the central portion of Figure 7, the plane of section extending in parallel to the plane of Figure 7.

Figure 9 is a side view of the needle, the cutter and the parts associated therewith, drawn to a larger scale.

Figure 10 is a plan.

Figure 11 is a similar view showing the 85 parts immediately after the cut.

Figure 12 shows half of a sole, the work to be done or being done being indicated by dotted lines.

Figure 13 is a front view of certain members forming part of a modification of the machine.

Figure 14 is a section on the line *d*—*d* in Figure 13.

Figure 15 is a section on the line *e*—*e* in 95 Figure 14.

Figure 16 is a section on the line *f*—*f* in Figure 14.

Figure 17 is a front view of the raising member, and

Figure 18 is a side view thereof.

Figure 19 is a section on the line $g-g$ in Figure 17, and

Figure 20 is a plan.

5 Figure 21 is a section on the line $h-h$ in Figure 19.

Figure 22 is a perspective view of said member.

Referring first to Figs. 1 to 12, the cutter block 1, in which a reciprocating cutter bar 2 is carried in a sleeve 1c, is provided with a vertical sleeve 1d adapted to receive the end of a presser bar 3. A spring 23 is inserted in the sleeve 1d and the hollow end of the bar 3 and tends to hold the cutter block 1 down on the sole 24 of the presser foot. A slotted extension 1a of the cutter block 1 engages a second guide bar 4 so as to prevent the cutter block 1 from turning about the bar 3.

20 A clamp 5 with a screw 8 is secured on the front end of the reciprocating cutter bar 2 in which the chuck 7, 9 for the cutter 10 is held by means of a pin 6. The chuck supports a finger or depressing member 33. This 25 finger or depressing member holds the work down on the work support and prevents the cutter from penetrating too deeply into the latter and also provides that incisions of uniform depth be obtained.

30 A bracket 11 is secured on the rear end of the reciprocating cutter bar 2 and connected with a slide 12 the front end of which is guided in a slot 13 of the cutter block 1. A sleeve 14 is free to turn on the cylindrical 35 rear portion of the slide 12, but held against axial displacement. A pin 14a is secured to the sleeve 14 and connected with the feed mechanism 17 by a ball and socket joint 15 which is linked to an arm 16a projecting 40 from the feed mechanism 17 by a pin 16, as will be seen in Fig. 6.

In the position of parts shown in end elevation in Fig. 7 and, on a larger scale and viewed from the rear in Fig. 7, in Fig. 9, the 45 feed dog 17a of the feed mechanism 17 has been lowered by the feed cam 17b and is ready to start for its return stroke. Its return stroke is the working stroke of the cutter 10. In the position shown in Fig. 9, the cutter 10 is immediately in front of the needle 18. On the return stroke of the feed mechanism, it is moved to the left for the length of one 50 stitch into its final position shown in dot and dash lines. During this stroke of the cutter, the work 19 remains stationary and the cutter makes a slit in the work. At the same 55 time, the flap which has been raised by the cutter to the rear of the needle 18 is folded down by a folder 20 which is secured to the sleeve 1c of the cutter block 1 by a clamp 21 and a screw 22. The folder 20 is exchangeable so that the machine may be adapted to 60 variations in the width of the slit. Before the feed mechanism starts on its working 65 stroke, the needle 18 is raised and the work is

engaged by the feed dog 17a and moved to the right in Fig. 9 for the length of one stitch. During the feed stroke, the cutter 10 and the folder 20 move with the work and assist the action of the feed dog 17a, the work being 70 engaged from above and below as in a pair of tongs.

On one side of the presser foot 24 there is provided the lug 25 bearing a stepped screw 26 carrying a lever 27 with a cam face 27a. The sleeve 1d of the block 1 is provided with a pin 28 located above this curve. 75

If the lever 27 is turned upwards by its handle 29, the cam face 27a lifts the pin 28 with its guide hub 1d and along with them the cutting mechanism connected therewith. The cutter block 1 can be lifted notwithstanding its connection with the feed mechanism 17 as the ball and socket joint 15 is free to turn on the slide 12 with its sleeve 14. The sole 24 of the presser foot remains on the work 19. Sewing may now be proceeded with without any cutting, the cutting mechanism being lifted, as described. 80

The sole 24 of the presser foot carries a 90 vertical pin 30 connected by an arm 31 with the presser bar at the hub 31a.

If the bar 3 is lifted by the lever 32, the sole 24 rises with the cutting mechanism so that the finished work is released for removal 95 and other work can be placed in position.

The cutter 10 (Figures 4a, 4b and 4c) essentially consists of the shank 10a extending obliquely in its working position (Figure 4c) and serving for attaching the cutter to its holder, and further of the horizontal blade 10b. The vertical edge 10c serves for lifting up the severed layer. In order to facilitate the lifting, the blade 10b is elongated beyond the lifting edge so that the point where the cutter cuts into the leather lies some distance in front of the point where the edge 10c commences to raise the severed layer which is now sufficiently loose and free at the point of lifting to permit being lifted with 110 but little pressure and without being upset. 110

The modification illustrated in Figures 13-22 is designed especially for work of hard material, such, for instance, as hard and dry kinds of leather. Such work involves the 115 danger that the pressure exerted by the cutter acts too strongly on the work and prevents it from being securely guided, in connection with the possibility that the needle is displaced from its correct position. The severed layer is further liable to become unequal in thickness and rough, while with very soft leather it tends to become wavy. The usual stationary roller serving as an abutment for the edge of the work entails further 120 disadvantages, inasmuch as the cutter does not remain exactly in the predetermined seam line. All these disadvantages are obviated by the following means. 125

The cutter bar 2 is again axially displace- 130

able in the block 1 which can be displaced on the presser bar 3. The pin 6 of the holder 7 carrying the cutter 10 can be clamped fast by means of a screw 8 at the front end of 5 the cutter bar in a suitable angular position.

In the sole 24 of the presser foot there is inserted the foot plate 45 of the raising member 41, the active part of which is connected 10 with the foot plate 45 by a bent arm 44, engages the slit in the work 19 with a tongue 42 and forms a guide for the needle 18 in the open groove 43 in order to prevent the needle from being pressed outwards by the severed 15 layer.

The edge of the work 19 is guided by a roller 47 which, however, is not supported in a stationary bearing, but is free to move together with the cutter 10. To this end the 20 roller 47 is adjustably attached to an arm 48 of the cutter holder 7, a clamping screw 49 forming the connecting member. Owing to this arrangement the roller 47 always remains in position in front of the place of cutting 25 and does not permit of the work giving way during the cutting.

I wish it to be understood that I do not desire to be limited to the exact details of construction shown and described, for obvious 30 modifications will occur to a person skilled in the art.

I claim:—

1. Cutting mechanism for sewing machines comprising a needle, means for reciprocating 35 said needle, a feed mechanism, a cutter bar adapted to reciprocate and operatively connected with said feed mechanism, a cutter capable of cutting at right angles to the reciprocation of the needle and in front 40 thereof, means for securing said cutter to said bar a finger secured to said cutter bar in front of said cutter and adapted to exert pressure on the work and means adjacent the stitching point engaging the needle for guarding 45 the same and lifting the severed portion of the work.

2. Cutting mechanism for sewing machines comprising a needle, means for reciprocating said needle, a feed mechanism, a cutter bar 50 adapted to reciprocate and operatively connected with said feed mechanism, a cutter capable of cutting at right angles to the reciprocation of the needle and in front thereof, means for securing said cutter to said bar, 55 a finger secured to said cutter bar in front of said cutter and adapted to exert pressure on the work, means above the work for supporting the cutter bar, said means being yieldingly pressed against the work, and a guide 60 roller carried by the cutter bar supporting means and movable up and down therewith for engaging the edge of the work and guiding the same.

3. Cutting mechanism for sewing machines 65 comprising a needle, means for reciprocating

said needle, a feed mechanism, a cutter bar adapted to reciprocate and operatively connected with said feed mechanism, a sleeve supporting said cutter bar, a cutter capable of cutting at right angles to the reciprocation of the needle and in front thereof, means for securing said cutter to said bar a folding ledge secured to said sleeve the rear of said cutter and means adjacent the stitching point 70 engaging the needle for guarding the same and lifting the severed portion of the work. 75

In testimony whereof I affix my signature.
HERMANN CHRISTIAN FISCHER.
